UNITED STATES PATENT OFFICE.

MICHAEL PARIDON, OF BARBERTON, AND JAMES H. WEAVER, OF WADSWORTH, OHIO,
ASSIGNORS TO THE OHIO MATCH COMPANY, OF WADSWORTH, OHIO, A CORPOR-
ATION OF OHIO.

MACHINE FOR BOXING MATCHES.

1,086,332.

Specification of Letters Patent.

Patented Feb. 3, 1914.

Original application filed April 4, 1913, Serial No. 758,989. Divided and this application filed July 25, 1913.
Serial No. 781,219.

To all whom it may concern:

Be it known that we, MICHAEL PARIDON and JAMES H. WEAVER, citizens of the United States, residing, respectively, at 5 Barberton, in the county of Summit and State of Ohio, and at Wadsworth, in the county of Medina and State of Ohio, have invented a certain new and useful Improvement in Machines for Boxing Matches, of 10 which the following is a full, clear, and exact description.

This case is a division of our case filed April 4, 1913, Serial No. 758,989, made in accordance with the requirement of the Patent Office.

The invention thus divided out relates to the shucking or sliding mechanism, same being the mechanism for assembling the filled trays and their shucks or covers.

20 In the accompanying drawings illustrating the invention, in the several figures of which like parts are similarly designated, Figure 1 is a plan view of the "sliding" mechanism, for applying the shuck to the filled tray, and a part of the tray carrier. Fig. 2 is a side elevation of a portion of the "sliding" mechanism including the shuck-carrier. Fig. 3 is a sectional elevation looking from the left of Fig. 2. Fig. 4 is a 25 sectional elevation, on a larger scale, of the upper right hand part of Fig. 3, showing the parts in full lines in position to unite the tray and shuck and showing these parts in dotted lines in position when the tray 30 and shuck are united and moved over into the shuck carrier to be discharged. Fig. 5 is a perspective view of the shuck hold-down. Fig. 6 is a top plan view of the parts shown in Fig. 4, some of the upper members being 35 broken out to expose those beneath, the parts being in the full-line position of Fig. 4. Fig. 40 7 is a perspective view of the throat members for alining the tray and shuck when being assembled.

45 The endless chain of tray holders 1, herein referred to as the "tray carrier," may be constructed and operated as in Patent No. 1,016,436, granted February 6, 1912. The table or bed 2 may be of appropriate 50 construction to receive and sustain the parts applied thereto. 3 is the discharge end of a trough leading from the tray feeding mechanism; 4 is a gravity push finger for moving the tray from the trough to the

tray carrier; 5 is a feed chain on which the 55 push finger is mounted; and 6 is a rod pivotally connected with a reciprocating push bar 7, pivoted to a crank-arm 8, which may be actuated in any suitable way, or as hereinafter described with reference to Fig. 3. 60 The sliding mechanism of this case comprises an endless shuck carrier located at or near one end of the table 2 at its side, and built up of shuck holders 9 having the parallel side flanges 10 and open ends, to 65 receive the shucks, and the standards 11, the horizontal bases of which standards are provided with transversely arranged gear teeth 12, and these bases are connected by similarly toothed links 13. The shuck carrier, 70 made up of these holders and links in endless chain form, is mounted upon polygonal idler drums 14, suitably mounted on the table, and it is driven by a mutilated gear wheel 15 which derives motion by bevel 75 gearing 16 from a shaft 17, which in turn is connected with any suitable source of power. The shucks are placed in the holders 9 in any suitable way, by hand or otherwise. The shuck carrier is timed to move 80 synchronously with the tray carrier, so as to present the shucks s, one at a time, opposite the filled trays t.

It will be understood that both the tray carrier and the shuck carrier have an intermittent or step-by-step motion, and as these carriers halt, they present the tray and shuck opposite a throat-piece 18, Fig. 7, into which the shuck is moved and held while the tray is inserted into the shuck. 85 This throat-piece comprises a base 19 fastened to the table and having vertically disposed cheek-pieces 20, and to these cheek-pieces are screwed the brackets 21 having the inwardly beveled rearwardly extended 90 cheek-pieces 22 of less width than the cheek-pieces 20, so as to leave vertically disposed stop shoulders 23 facing in the direction of the moving shuck, so as to arrest or stop the shuck at the proper place and in the 100 correct position to be entered by the tray. The cheek-pieces 22 correct the alinement of any shucks that may be askew in the holders and straighten them out so as to enter the throat-piece in alinement with the 105 tray. The cheek-pieces 20 are likewise beveled in the direction of the approaching tray, and similarly serve to correct any

askewness of the trays and center them in the throat-piece in alinement with the shuck, all as shown more particularly in Fig. 6.

From the brackets 21 depends a tongue 24 with a tip 25 that projects into the near open end of the shuck to insure the openness of the shuck and to guide the tray into the shuck. This tongue is preferably pivotally mounted so as to swing away from the shuck and be caught by the approaching tray, and by it lifted into the open end of the shuck to insure the entrance of the tray into the shuck. The brackets 21 may be further connected by a cross-bar 26 and this cross-bar may be used to prevent the undue upward movement of the tongue 24.

The push bar 7, which actuates the feed chain, has its forward end depressed, as at 27, and provided with a vertically disposed shoulder 28; and said bar is also provided with a cam block 29 which cooperates with a roller 30 mounted on the bracket 31 fast to the table, so that as the crank-arm 8 is vibrated, the bar 7 will have a longitudinal reciprocating motion, and as its cam block 29 rides over the roller 30, the shoulder 28 will be dropped into line with the tray on the tray carrier, and upon a further movement in the same direction, the tray will be pushed off of its holder into the shuck, and the shuck with the tray inclosed will, by further movement of the bar in the same direction, be pushed over and substantially centered in the holder of the shuck carrier ready to be carried forward or discharged. The forward end of the depressed portion 27 carries a tongue 32 which as the bar 7 drops over the roller 30, comes down on top of and covers the tray full of matches, and holds the tray steady, with its contents intact, as the tray is being pushed beneath the tongue 24 into the shuck. The bar 7 may drop by its own weight, but it is preferable to use force to cause it to drop. A simple means to this end is a spring-pressed roller 33, mounted upon a stand 34 rising from the frame,—see Figs. 1 and 3.

The coöperating shuck-moving parts comprise an arm 35 which is pivotally mounted upon the upper end of a lever 36 mounted on a stud 37 and vibrated by a cam 38 on the shaft 39. This arm 35 is supported at its outer end by a yoke 40 which straddles the throat-piece, substantially as shown in Fig. 2, and said arm is held against vertical movement in the yoke by means of a plate 41 attached to the yoke beneath said arm. The outer end of this arm is provided with a push piece 42. Straddling the outer end of this arm is a yoke 43, and this yoke is carried by a spring 44 bent around the knuckle of the arm 35 as shown in Fig. 3, or screwed to said arm as shown in Fig. 4, or otherwise mounted so as to move back and forth with the arm. The spring 44 carries an inclined

block 45 which is adapted to coöperate with the inclined top 46 of the yoke 40, so that as the arm 35 is moved longitudinally, the block 45 will ride up the inclined top 46 and serve to lift the yoke 43, and, reversely, when the arm 35 is moved in the opposite direction, the block 45 will ride off of the incline 46 allowing the resiliency of the spring to operate to lower the yoke 43. As soon as the lever 36 is moved to the left, Figs. 3 and 4, from the position shown in full lines, Fig. 3, and the cam block 45 moves down the incline 46 to substantially the position shown in dotted lines, Fig. 4, then the yoke 43 will descend into position to engage the shuck and hold it down in its holder in the shuck carrier, and at the same time the push piece 44 will come into end engagement with the shuck, and then, by further movement of the arm 35 to the left, the shuck will be moved into the throat-piece, as shown in Figs. 4 and 6, and arrested there while the tray, by the further movement of the bar 7 toward the right, is moved into the shuck. When this is accomplished the lever 36 begins its return movement toward the right, and the bar 7 continues its motion to the right and the assembled tray and slide are moved over centrally of the shuck carrier, as indicated in dotted lines in Fig. 4, and ready to be carried forward for discharge onto the conveyer, whence it is ready for the wrapper.

The yoke 43 may be provided with any convenient means for grasping the shuck, and as shown in Figs. 4 and 5, its lower ends may be provided with the beveled pieces 47 which engage the sides of the shuck and the transversely arranged pieces 48 which may be provided with beveled edges of sufficient sharpness to bite the edges of the shuck and hold it definitely in place, while the tray is being inserted in it, and to assist in its movement into and out of the throat.

The yoke 43 with its appurtenances is herein referred to as a hold-down, because of its functions in positioning and retaining the shuck in the sliding operation.

As shown in Figs. 1 and 2, a conveyer trough 49 may be arranged at the discharge end of the shuck carrier into which the assembled parts may be discharged from such carrier. This conveyer is located slightly above the level of and in line with the slide carrier; and in order to insure the discharge of the filled and covered boxes from the shuck carrier, inclined ways 50 are located on opposite sides of the shuck carrier beneath and in line with the oppositely projecting ends of the shucks in said carrier, so that as said carrier advances the boxes toward the conveyer 49, these boxes are gradually lifted out of the shuck holders by said inclined ways, and the succeeding boxes push those in advance on to the conveyer,

whence they may be taken by an attendant and wrapped or packed.

Since both the tray holders and the shuck holders are not as long as the trays and shucks, these box elements extend beyond their respective holders, and thus have free adjacent ends for assembly purposes.

As shown more particularly in Figs. 1, 2 and 3, guards 51 of substantially Z shape in cross-section are arranged along opposite sides of the tray carrier in advance of the sliding mechanism, and these guards serve the double purpose, first, of holding the trays centrally within the holders between the point where the usual protection strips are applied over the matches in the trays and the point where the sliding is done, and second, guarding the ends of the moving holder so as to prevent the operator's fingers from being caught between the moving parts and the stationary parts of the machine near which the links of the tray carrier pass.

As already stated, the crank arm 8 may be actuated in any suitable way, but referring to Fig. 3, this arm may be fixed to a rock-shaft 52 having a rocker-arm 53 in roller engagement with a cam 54 on the shaft 39.

As already sufficiently indicated, we do not limit our invention to structural details excepting as these are specifically claimed, but our invention consists rather in the principles of structure whereby the trays when filled are supplied with their appropriate shucks.

What we claim is:—

1. In a match machine, sliding mechanism for assembling the filled trays and their shucks, including in combination with an endless traveling tray carrier provided with a series of connected individual tray holders, an endless traveling shuck carrier arranged parallel to the tray carrier and provided with a series of connected individual shuck holders, means interposed between these carriers to align the trays and the shucks, and means arranged at right angles to the carriers to transfer the filled trays successively into the shucks.

50 2. In a match machine, sliding mechanism for assembling the filled trays and their shucks, including in combination with an endless traveling tray carrier provided with a series of connected individual tray holders, an endless traveling shuck carrier arranged parallel to the tray carrier and provided with a series of connected individual shuck holders, means for positively gripping and detaining the shucks in the shuck carrier one at a time, and means for inserting a filled tray into the detained shuck.

3. In a match machine, sliding mechanism for assembling the filled trays and their shucks, including in combination with an

endless traveling tray carrier provided with a series of connected individual tray holders, an endless traveling shuck carrier arranged parallel to the tray carrier and provided with a series of connected individual shuck holders, a reciprocating pusher arm arranged transversely to the carriers and adapted to act successively upon the shucks in the shuck carrier, and a reciprocating tongue and tray pusher also arranged transversely to the carriers and adapted to act upon the filled trays in the tray carrier successively for assembling the trays and shucks.

4. In a match machine, the combination of a tray carrier and a shuck carrier arranged side by side, means to move these carriers in the same direction intermittently, a throat piece interposed between the carriers, and means to move a tray from the tray carrier and a shuck from the shuck carrier substantially simultaneously into the said throat piece, said throat piece serving to align the tray and shuck, the tray moving means being capable of further movement in the same direction to insert the tray within the shuck.

5. In a match machine, the combination of a tray carrier and a shuck carrier arranged side by side, means to move these carriers in the same direction intermittently, a throat piece interposed between the carriers, and means to move a tray from the tray carrier and a shuck from the shuck carrier substantially simultaneously into the said throat piece, said throat piece serving to align the tray and shuck, the tray moving means being capable of further movement in the same direction to insert the tray within the shuck, said tray moving means capable of still further movement for moving the assembled tray and shuck out of the throat piece and into a position on the shuck carrier that will admit of their removal from the machine.

6. In a match machine, the combination of a tray carrier and a shuck carrier arranged side by side, means to move these carriers in the same direction intermittently, a throat piece interposed between the carriers, and means to move a tray from the tray carrier and a shuck from the shuck carrier substantially simultaneously into the said throat piece, said throat piece serving to align the tray and shuck, the tray moving means being capable of further movement in the same direction to insert the tray within the shuck, said shuck moving means including a shuck hold-down for holding the shuck against movement while the tray is being inserted.

7. In a match machine, the combination of a tray carrier and a shuck carrier arranged side by side, means to move these carriers in the same direction intermittently,

- a throat piece interposed between the carriers, means to move a tray from the tray carrier and a shuck from the shuck carrier substantially simultaneously into the 5 said throat piece, said throat piece serving to align the tray and shuck, the tray moving means being capable of further movement in the same direction to insert the tray within the shuck, and a shuck opener arranged 10 in the throat piece and operating under the advance of the tray into the shuck.
8. In a match machine, the combination with a traveling tray carrier and a traveling shuck carrier arranged side by side, of an 15 interposed stationary throat piece having cheek-pieces to align the tray and shuck as they are moved into the said throat piece, and means to move said tray and shuck toward each other.
- 20 9. In a match machine, the combination with a traveling tray carrier and a traveling shuck carrier, of a throat piece adapted to align the tray and shuck as they are moved toward each other, a shuck opener arranged 25 in said throat piece, and a reciprocating member having a tongue for holding down the matches in the tray and a shoulder for moving said tray into the shuck.
10. In a match machine, the combination 30 with a traveling tray carrier and a traveling shuck carrier, of a throat piece adapted to align the tray and shuck as they are moved toward each other, a shuck opener arranged 35 in said throat piece, a reciprocating member having a tongue for holding down the matches in the tray and a shoulder for moving said tray into the shuck.
11. In a match machine, the combination 40 with a traveling tray carrier and a traveling shuck carrier arranged side by side, interposed means to align the tray and shuck for assembly purposes, and a shuck moving element comprising a longitudinally reciprocating arm, a spring-supported hold-down carried by said arm and moving with it and adapted to engage the shuck, and means to permit said hold-down to engage the shuck and to effect its disengagement.
12. In a match machine, the combination 45 with a traveling tray carrier and a traveling shuck carrier arranged side by side, interposed means to align the tray and shuck for assembly purposes, and a shuck moving element comprising a longitudinally reciprocating arm having a push piece to engage the outer end of the shuck, a spring-sup- 50 ported hold-down carried by said arm and moving with it, and means to permit said hold-down to grasp the shuck and thereafter to release it.
13. In a match machine, the combination 55 with a traveling tray carrier and a traveling shuck carrier, of a throat piece adapted to align the tray and shuck as they are moved toward each other, a shuck opener arranged in said throat piece, a reciprocating member having a tongue for holding down the 60 matches in the tray and a shoulder for moving said tray into the shuck, and means to hold the shuck in position in the throat piece while the tray is being inserted into said shuck, including a hold-down provided with means to engage the sides of 65 the shuck and additional means to engage the top of the shuck.
14. In a match machine, the combination 70 with a traveling tray carrier and a traveling shuck carrier arranged side by side, interposed means to align the tray and shuck for assembly purposes, and a shuck moving element comprising a longitudinally reciprocating arm having a push piece to engage 75 the outer end of the shuck, a spring-supported hold-down carried by said arm and moving with it and adapted to engage the shuck, a stationary incline, and a complementary inclined block carried by the 80 spring and coöperating with said stationary incline to raise and lower the hold-down.
15. In a match machine, a sliding mechanism for use in assembling the shucks and trays, including an endless chain of holders, 85 polygonal drums on which they are mounted and over which they travel, and inter-engaging toothed parts arranged respectively upon the endless chain of holders and a driver therefor for intermittently moving 90 the endless chain of holders.
16. In a match machine, a sliding mechanism including a series of holders and a series of connecting links united in an endless chain, the holders and links provided 95 with teeth, polygonal drums on which said endless chain is mounted, and a mutilated intermittently driving gear coöperating with the teeth on the holders and links for moving the endless chain over the drums.
- In testimony whereof we have hereunto set our hands this 21st day of July A. D. 1913.

MICHAEL PARIDON.
JAMES H. WEAVER.

Witnesses:

J. A. CRUMRINE,
S. M. BECK.

It is hereby certified that in Letters Patent No. 1,086,332, granted February 3, 1914, upon the application of Michael Paridon, of Barberton, and James H. Weaver, of Wadsworth, Ohio, for an improvement in "Machines for Boxing Matches," errors appear in the printed specification requiring correction as follows: Page 4, line 108, strike out the word "intermittently"; same page, line 109, after the word "for" insert the word *intermittently*; and that the said Letters Patent should be read with these corrections therein that the same may conform to the record of the case in the Patent Office.

Signed and sealed this 17th day of February, A. D., 1914.

[SEAL.]

J. T. NEWTON,
Acting Commissioner of Patents.
